UNITED STATES PATENT OFFICE.

ARTHUR TREVOR DAWSON AND LOUIS SILVERMAN, OF LONDON, ENGLAND, ASSIGNORS TO VICKERS SONS & MAXIM, LIMITED, OF WESTMINSTER, ENGLAND.

QUICK-FIRING GUN.

SPECIFICATION forming part of Letters Patent No. 738,666, dated September 8, 1903.

Application filed March 7, 1903. Serial No. 148,752. (No model.)

To all whom it may concern:

Be it known that we, ARTHUR TREVOR DAWSON, lieutenant of the Royal Navy, director and superintendent of Ordnance Works, and 5 LOUIS SILVERMAN, engineer, subjects of the King of Great Britain, residing at 32 Victoria street, Westminster, in the county of London, England, have invented certain new and useful Improvements Relating to Quick-Firing Guns, of which the following is a specification.

This invention has reference to quick-firing guns, particularly those of the kind in which there is a transversely-sliding breech-block and in which the cartridges are supplied to the gun by a hinged cartridge-carrier situated immediately below a hopper, which carrier at the proper times descends with a cartridge and brings the same in alignment with 15 the charge-chamber, when by the action of a spring piston or pusher the cartridge is projected or thrown from the carrier into said charge-chamber, as explained in the specifications of some of our prior patents, of which 20 No. 644,969 is an example.

One part of our invention has reference to various improvements in the cartridge-carrier and the parts in connection therewith. One of these improvements has for its object 25 to prevent the cartridge in the carrier from becoming displaced by vibration of the parts during the firing of the gun or the forward portion of said cartridge from unduly rising in the carrier and the carrier from descending without the cartridge. Another of these 30 improvements has for its object to shift the cartridge longitudinally forward in the carrier during the descent of the latter, this shifting of the cartridge being effected by a lever contrivance instead of by a curved surface at the rear end of the carrier, as before. Another of these improvements has for its 35 object to prevent the hinged catch, pawl, or striker of the spring piston or pusher from missing the lug with which it must engage when in its "cocked" position, such missing being liable to occur by the vibration of the said striker about its hinge during the working of the gun and during the time the piston is being retracted by the recoiling gun to compress the spring of said piston. Another of

these improvements has for its object to enable the carrier to be readily detached, together with the hopper, so that the gun can then work as a semi-automatic gun.

Another part of our invention has reference to the manner in which the shoulder-piece of the gun is connected with its stem, so that when the gun is being fired the gunner can push the shoulder-piece forwardly 60 against the resistance of the aforesaid piston-spring, which will then serve as a buffer to assist in absorbing the shock or vibration when the gun is fired.

In order that our said invention may be 65 clearly understood and readily carried into effect, we will describe the same more fully with reference to the accompanying drawings, in which—

Figure 1 is a side elevation, partly in section, and Fig. 2 a plan, of an automatic quick-firing gun provided with our improvements. Fig. 3 is a vertical longitudinal section of the breech end of the gun drawn on a larger scale. Fig. 4 is a side elevation, and Fig. 5 a cross-section on the line 1 1 of Fig. 4, showing the device for preventing the cartridge from becoming vertically displaced in the carrier. Figs. 6 and 7 are sectional elevations showing the device for shifting the cartridge longitudinally forward in the carrier as the latter descends, Fig. 6 representing the carrier raised and Fig. 7 the carrier lowered. Figs. 8 and 9 are side elevations showing the means for preventing the striker of the spring piston or pusher from participating in unnecessary movement about its hinge, these figures respectively representing the striker fully retracted and engaged with its lug. Fig. 10 is a central vertical section taken through the forward part of the spring piston or pusher. Fig. 11 is a horizontal section showing how the shoulder-piece is connected with its stem in order to permit of its being pushed forward against the resistance of the pusher-spring 95 to enable the latter to serve as a buffer when the gun is being fired. Fig. 12 is a side elevation of the hopper with the carrier hinged thereto instead of to the stem of the crutch, as heretofore.

In all the figures like letters of reference indicate similar parts.

A is the recoiling gun-barrel, and A' the frame or casing in which it recoils.

B is the breech-block, which is adapted to slide vertically to open and close the breech 5 by the operation of the block-actuating arm B', which is carried by a transverse shaft B², that turns in one direction by the recoiling movement of the barrel and in the other direction by the reaction of a spring contained 10 in a box or casing B³, as is well understood.

C is the cartridge-case extractor, which is mounted on the axle C' and has the toe-piece C² for engagement with the cam B⁴ on the shaft B² when the block descends into its 15 fully-opened position, thereby maintaining the breech open until a fresh cartridge in entering the breech-chamber releases said extractor from the said cam B⁴ and permits the aforesaid spring to react and cause the block 20 to rise and close the breech.

D is the firing-pin, which works in a cavity B⁵ in the block and is coupled to the firing or cocking arm E, pivoted to the block at E'.

F is the sear, pivoted to the block at F' 25 and having a tail F², which is acted upon by the firing mechanism.

G is the mainspring, the longer member of which bears against the cocking-arm E and the shorter member against the sear F.

30 H is the lifting-lever, which is hinged at H' to the gun-barrel and is controlled by the breech-block for lifting the hinged cartridge-carrier I as the block rises and releasing said carrier as it descends.

J is the cartridge-hopper.

K is the shoulder-piece. L is the stem thereof, which is hollow and contains the piston M and its spring M'. M² is the striker, hinged to said piston and operating to project the 40 cartridge from the carrier when released from a stop L' on the stem L.

N is the brake-cylinder.

O is the trigger of the firing mechanism.

The cartridge-carrier I is hinged at I' to the 45 stem of the shoulder-piece and receives its movement about said hinge by the action of the lifting-lever H in an analogous manner to that explained in the aforesaid prior specification. About midway of the length of the 50 said carrier; Figs. 4 and 5, we provide a pawl or catch i, which is acted upon by a spring i', that normally tends to keep lateral stops i² on the pawl pressed against recessed lugs i³, in which said pawl is mounted, whereby said 55 pawl occupies the position represented in Fig. 5. When, however, the lowermost cartridge escapes from the hopper J (as it does when the carrier rises and actuates the escapement device j, as is well understood in 60 guns of this kind) and falls into the carrier, the said pawl i will give way and permit the cartridge to pass, but will immediately after resume its original position under the action of its spring, in which position it will effectually prevent the cartridge from unduly rising in the carrier should it tend to do so. The 65 cartridge will thus be compelled to remain in

the carrier while the latter is descending into loading position, so that when projected from said carrier by the spring-pusher M it will be 70 directed properly into the breech-chamber.

Mounted on the hinge-pin I' of the cartridge-carrier is a crank I², (see Figs. 6 and 7,) said pin and crank being stationary. To the free end of said crank is hinged by a pin I³ a 75 rod or finger I⁴, the free end of which lies within and is supported by an aperture I⁵ in the rear end of the cartridge-carrier. When the carrier is in its raised position, Fig. 6, the said free end of the rod or finger I⁴ 80 only slightly protrudes (if at all) through the aperture I⁵, so that it offers no impediment to the passage of the lowermost cartridge from the hopper into the carrier. When, however, the said carrier is permitted to descend into its loading position, Fig. 7, the free end of the rod or finger I⁴ is caused to protrude to a considerable extent through the aperture I⁵ by reason of its eccentric connection with the hinge-pin I'. In so doing 85 said rod or finger pushes the cartridge in the carrier longitudinally forward to cause its flange or rim to come under the internally flanged or beaded edges i² of the carrier, said flanged or beaded edges serving to guide the 90 cartridge during the time it is being projected from the carrier into the charge-chamber. The said striker M² is formed with a hinge-pin m, (see Figs. 8, 9, and 10,) which is adapted to enter a transverse hole in the head of 100 the piston M. This hinge-pin is formed with a recess the bottom m' of which is inclined to the vertical. The said transverse hole is formed with an opening through which a flat-ended prolongation m² on a disk m³ projects 105 and engages with the aforesaid recess of the hinge-pin m. The said disk is kept in position by the spring M', and the pressure of this spring also acts to keep the flat end of the prolongation m² pressed against the inclined 110 bottom m' of the recess, so that the striker M² is constantly tending to turn upwardly. The opposite or free end of the said striker has a shoulder m⁴, which under the influence of the aforesaid spring M', acting through the 115 aforesaid hinge connection, engages with a fixed lug L' on the stem L of the shoulder-piece, thereby keeping the spring-piston retracted when it has been pushed backward by the gun-barrel during its recoil movement. 120 The free end of said striker also has a lateral finger m⁵, which when the striker is liberated from the lug L' enters (under the action of the spring M') an elongated hole in the carrier and strikes the base of the cartridge contained therein, thus projecting the latter from the carrier into the breech-chamber. This 125 liberation of the striker from the lug L' is effected by the carrier acting on the lateral pin or projection m⁶ of the striker as said carrier falls from its raised position to its loading position by the opening movement of the breech-block and the descent of the lifting-lever H. Situated on the stem L of the shoul-

der-piece, at a point below the free end of the striker when it is in its engaged or cocked position, Fig. 9, is a lateral stop L^2 , the distance of which from said free end of the striker is such that it will only allow the latter to fall under the weight of the carrier far enough to liberate the shoulder m^2 of the striker from the lug L' . The said stop L^2 limits the extent of movement in which the striker can participate while it is performing the last part of its rearward movement, so that the vibration to which the parts of the gun are subjected when in action will not be able to shift the shoulder m^2 into a position of non-alignment with the lug L' , thereby avoiding any chance of the striker missing its engagement with said lug.

The connection of the shoulder-piece with its stem L , Fig. 11, is effected by a cup-shaped piece K' on the crutch-entering the socketed end L^3 of the stem, said cup-shaped piece serving to receive the outer end of the piston-spring.

k is a flat pin or cotter passing through elongated holes in the stem L and the cup-shaped piece K' . The elongated holes in the stem L are of such dimensions as to enable the pin or cotter to tightly fit the same; but the elongated hole in the cup-shaped piece K' is greater in length than the width of the pin or cotter k , Fig. 11, so that the said cup-shaped piece is free to slide within the stem to a limited extent. When the gunner in firing the gun presses his shoulder against the shoulder-piece K , he forces the cup-shaped piece forward against the resistance of the piston-spring, which therefore assists in preventing the shock and vibration due to the firing of the gun from being too forcibly transmitted to the gunner.

In some cases the hopper J and carrier I may be made as shown in Fig. 12, wherein the said hopper is provided with a rearwardly-extending lug J' , which carries the hinge-pin I' , on which the cartridge-carrier I is mounted so as to turn thereon, as already explained. By this arrangement the hopper and cartridge-carrier form a composite piece that can be readily removed from the socket l of the stem L of the shoulder-piece when it is desired to work the gun semi-automatically. In order to assist in steadyng the hopper, it may have near its rear part a lateral pin j^2 , which is adapted to engage with a slotted lug l' on the stem L when the hopper is in place, or, if desired, two of the steadyng-sockets l may be provided on the stem L and the hopper may be furnished with corresponding projections near its opposite ends for engagement therewith.

What we claim, and desire to secure by Letters Patent of the United States, is—

1. In a quick-firing gun, the combination with a cartridge-hopper and a hinged trough-shaped cartridge-carrier adapted to swing to and fro with respect to said hopper, in order to transfer the cartridge from the hopper to

the loading position, of means whereby the forward portion of the cartridge is prevented from unduly rising in the carrier substantially as described.

2. In a quick-firing gun, the combination with a cartridge-hopper and a hinged trough-shaped cartridge-carrier adapted to swing to and fro with respect to said hopper in order to transfer the cartridges from the hopper to the loading position, of a catch mounted on the carrier and adapted to move in a plane at right angles to the longitudinal axis of the carrier, and means whereby said catch can move inwardly under the weight of a cartridge falling from the hopper into the carrier but cannot move outwardly beyond a limited extent substantially as and for the purpose specified.

3. In a quick-firing gun, the combination with a cartridge-hopper and a hinged trough-shaped cartridge-carrier adapted to swing to and fro with respect to said hopper in order to transfer the cartridges from the hopper to the loading position, of longitudinal beads extending along the edges of the said trough-shaped carrier and means exterior with respect to the carrier for pushing the rim or flange of the cartridge beneath said beads as the carrier assumes its loading position substantially as described.

4. In a quick-firing gun, the combination with a cartridge-hopper and a hinged trough-shaped cartridge-carrier adapted to swing to and fro with respect to said hopper in order to transfer the cartridges from the hopper to the loading position, of longitudinal beads extending along the edges of the said trough-shaped carrier, and a finger eccentrically hinged at a point below the hinge of the carrier with its free end extending into an opening in the rear of the carrier substantially as and for the purpose specified.

5. In a quick-firing gun, the combination with a cartridge-hopper, a hinged trough-shaped cartridge-carrier adapted to swing to and fro with respect to said hopper in order to transfer the cartridges from said hopper to the loading position, a stem carrying said hopper and carrier, a spring-controlled piston within the said stem adapted to be retracted by the recoil movement of the gun, a striker hinged to said piston, a lug with which said striker engages to keep the piston retracted until the carrier releases the striker in assuming the loading position, and a stop on the said stem which stop is located in a position to support the striker during the completion of the retractive movement of the spring-piston, so that the vibration to which said striker is subjected during the working of the gun will be prevented from causing the striker to miss its engagement with said lug substantially as described.

6. In a quick-firing gun, the combination with the cartridge-hopper, of a cartridge-carrier hinged to said hopper so as to oscillate in a plane longitudinal with respect to the

hopper, and means for detachably connecting the said hopper to the stem of the shoulder-piece of the gun, substantially as and for the purpose described.

5 7. In a quick-firing gun, the combination with the cartridge-hopper, of a trough-shaped cartridge-carrier hinged at its rear end to said hopper so as to oscillate in a plane longitudinal with respect to the hopper, means for detachably connecting said hopper to the stem of the shoulder-piece of the gun, and means for steadyng said hopper when in position, substantially as described.

8. In a quick-firing gun, the combination 15 with the cartridge-hopper, of an oscillatory trough-shaped cartridge-carrier hinged at its rear end to a transverse pivot-pin on said hopper, means for detachably connecting said hopper to the stem of the shoulder-piece of 20 the gun, a forked lug on said stem and a projection on said hopper to engage with the

forked lug when the hopper is in position, substantially as described.

9. In a quick-firing gun, the combination with the stem of the shoulder-piece, the 25 striker-piston and its spring, of means for loosely connecting the shoulder-piece to the stem and for permitting it to be pushed inward against the resistance of the spring of the striker-piston, thus enabling said spring 30 to intercept the shocks between the gun and the shoulder-piece during the working of the gun, substantially as described.

In testimony whereof we have hereunto set our hands, in presence of two subscribing witnesses, this 20th day of February, 1903.

ARTHUR TREVOR DAWSON.
